UNITED STATES PATENT OFFICE

LAURITS DINESEN, OF MINNEAPOLIS, MINNESOTA

ROTARY PUMP

Application filed February 28, 1927. Serial No. 171,478.

My present invention has for its object to provide an extremely simple and highly efficient vibrationless rotary pump or motor that can be operated at high speed, and to such ends, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a front elevation showing one form of the invention;

Fig. 2 is a view principally in central vertical section;

Fig. 3 is a plan view of the same;

Fig. 4 is a view partly in section taken on the line 4—4 of Fig. 2;

Fig. 5 is a rear elevation of the rotor removed from the casing;

Fig. 6 is a perspective view of the rotor with a portion of its shaft broken away;

Fig. 7 is a perspective view of the piston removed from the rotor;

Fig. 8 is a view of the piston in section taken on the line 8—8 of Fig. 7;

Fig. 9 is a perspective view of the trunnion and its coupling head;

Fig. 10 is a view principally in horizontal central section showing another form of the invention;

Fig. 11 is a view partly in elevation and partly in section taken on the line 11—11 of Fig. 10; and

Figs. 12 and 13 are perspective views showing, respectively, one of the pistons and the coupling head-equipped trunnion removed from the pump shown in Figs. 10 and 11.

Referring first to the invention as illustrated in Figs. 1 to 9, inclusive, the numeral 14 indicates a cylindrical casing having a supporting base 15 adapted to be bolted to a bed or other support.

The front of the casing 14 is in the form of a removable head 16 held in place by a plurality of screws and having a bearing 17 closed at its outer end. Formed with the back of the casing 14 is a long bearing 18 having a stuffing box 19. It is important to note that

the axes of the bearings 17 and 18 are parallel and that the axes of the bearing and the casing 14 are aligned and that the axis of the bearing 17 is eccentric thereto. Formed with the casing 14 are bossed, internally screw-threaded intake and discharge pipe-attaching openings 20 and 21, respectively.

Mounted in the casing 14 is a cylindrical rotor 22 which completely fills said casing with just enough clearance at its sides and periphery to run freely. A shaft 23 driven from an electric motor or other vise has its inner end portion journaled in the bearing 18 and rigidly secured to the rotor 22 at the back thereof and in axial alignment therewith. Formed in the inner cylindrical face of the casing 14 are radial intake and discharge ports 24 and 25, the former of which leads from the intake opening 20 and the latter of which leads to the discharge opening 21. The casing 14 has diametrically opposite port closing surfaces 26 and 27 which separate the ports 24 and 25.

A double-acting piston 28 is mounted in a seat 29 formed in the face of the rotor 22 and extends diametrically therethrough and corresponds to the customary piston cylinder. Said piston 28 is rectangular in cross section and its seat 29 is correspondingly formed. An axially located cavity 30 is formed in the face of the rotor 22 and is somewhat shallower than the seat 29 so that the sides of said seat are continuous and engage the piston 28 throughout its entire length. The cylinder head 22 holds the piston in its seat 29 and said piston has a pair of pockets 31 in its back and also in its face for holding a lubricant.

The piston 28 is held to turn about an axis eccentric to the axis of the rotor 22, with freedom for lateral shifting movement, by a trunnion 32 mounted in the seat 17 and having a coupling head 33, with flattened sides, which is mounted in a transverse seat 34 formed in the face of the piston 28 at the longitudinal center thereof. Said coupling head 33 and seat 34 separably connect the piston 28 and trunnion 32 for common rotation but permit free lateral shifting movement of said piston on the coupling head 33 produced by the ro-

tation of the rotor 22 and piston 28 on eccentric axes.

The liquid passing through the pump keeps the movable parts thereof lubricated, and an axial duct 35 extends completely through the trunnion 32 and its coupling 33 through which sufficient liquid in the casing 14 is conveyed to the outer end of the seat 17 to keep the trunnion 32 lubricated. The liquid in the casing 14 picked up by the pockets 31 keeps the piston 28 lubricated.

Once during each one-half rotation of the rotor 22 both ends of the seat 29 are simultaneously closed by the casing surfaces 26 and 27 and in this position of the rotor 22, the end of the seat 29 closed by the casing surface 27, which is between the receiving end of the intake port 24 and the delivery end of the discharge port 25, is empty and completely closed by the piston 28. The other end of the seat 29, which is closed by the casing surface 26, is open to its full intake capacity and completely filled with liquid. During the balance of each half rotation of the rotor 22, said rotor, by its peripheral contact with the casing surfaces 26 and 27, separate the ports 24 and 25.

The rotor 22 is turned in the direction of the arrow marked thereon in Fig. 4 and as the piston seat 29 is moved out of registration with the casing surfaces 26 and 27 the end of said seat in communication with the port 24 is gradually open and filled with liquid, and by the time it reaches the casing surface 26 it is completely open and filled. At the same time the other end of said seat 29, which is filled with liquid, is being closed by the piston 28 and the liquid therein discharged into the port 25 and through the discharge opening 21.

To adapt the above described rotor pump for use in connection with oil burners or for other uses where it is necessary to deliver a small quantity of oil, which is very difficult to do by a continuous stream, I accomplish the desired result by an intermittent action. This feature of my pump includes a passage 36, a port 37, and a by-pass 38. The passage 36 leads from the discharge port 25 and is formed in the casing 14, at the top and back thereof, and the port 37 is formed in said casing and leads from the interior thereof, back of the rotor 22, to a bossed discharge opening 40 in said casing, that is internally screw-threaded to receive and hold a discharge pipe, not shown. The by-pass 39 is formed in the back of the rotor 22 and is arranged to connect the passage 36 with the port 37 once during each rotation of said rotor.

A needle valve 41 for the port 37 is provided to vary, at will, the liquid-conducting capacity of said port.

Obviously, each time the by-pass 38 connects the port 37 with the passage 36 a small

amount of liquid is discharged into the opening 40 from the discharge port 25. As only a very small quantity of the liquid passing through the pump is delivered to the discharge opening 40 the balance of said liquid passing through the discharge opening 21 may be used for any desired purpose or it may be returned to the supply tank.

Referring now to the invention shown in Figs. 10 to 13, inclusive, the construction is substantially the same as that shown in Figs. 1 to 9, inclusive, with the exception that the rotor 42 is provided with two double-acting pistons 43 and 44 that extend at right angles to each other and are mounted in diametrically opposite seats 45 and 46 in the opposite side of said rotor. The rotor 42 is mounted in a casing 47 having a displaceable head and a stuffing box-equipped bearing 49 in which the driven shaft 50 of the rotor 42 is journaled. The pistons 43 and 44 are mounted in the same plane and have in their opposing faces relatively large transverse passages 51 which permit said pistons to fit, the one within the other, with freedom for independent transverse shifting movements. Said pistons 43 and 44 are further provided at the backs of their passages 51 with transverse seats 52 in which is mounted a coupling block 53 slidably mounted on a trunnion 54 on the inner faces of the head 48, and extends through an oblong aperture 55 in the piston 43. The piston 44 is also provided with a like aperture 56 which makes the two pistons 43 and 44 duplicates so that they may be interchangeably used. The axis of the trunnion 54 is eccentric with the axis of the rotor 42 and its coupling blocks 53 holds said pistons for common rotation about the axis of said trunnion with freedom for independent transverse shifting movements.

The trunnion 54 is provided with a duct 57 for the passage of a lubricant in the casing 47 through the aperture 56 and from thence to the back of the piston 44. Radial intake and discharge ports 58 and 59 are formed in the casing 47 with port-separating surfaces 60 formed with said casing. Formed with the casing 47 is a bossed internally screw-threaded opening 61 which opens into the intake port 58 for connecting a supply pipe thereto, and an internally screw-threaded bossed opening 62 is formed in the casing 47 for connecting a discharge pipe to the discharge pipe 49.

What I claim is:

1. In a rotary pump, a casing, a rotor in the casing having a piston seat extending diametrically thereof, a piston mounted in said seat and having an intermediate transverse seat, a trunnion eccentric to the axis of the rotor and having a flat coupling head extending into the seat in the piston and holding said piston to turn about the axis of the trunnion but permitting lateral shifting

movement thereof, said trunnion and its head being mounted to rotate with said piston.

2. In a rotary pump, a casing having an intake passage and a discharge passage, a port leading from the intake passage to the casing, and a rotor having a by-pass arranged to intermittently connect the port with the discharge passage during the rotation of said rotor.

10 3. The structure defined in claim 2 in further combination with a choke valve for the port.

In testimony whereof I affix my signature.

15 LAURITS DINESEN.
